(57) **CLAIM**

The ornamental design for a packaging container, as shown and described.

DESCRIPTION

FIG. 1 is a perspective view;

FIG. 2 is a top plan view;

FIG. 3 is a bottom plan view;

FIG. 4 is a front elevational view;

FIG. 5 is a rear elevational view;

FIG. 6 is a left side elevational view;

FIG. 7 is a right side elevational view;

FIG. 8 is a top plan view showing a state in which an outer cap is removed;

FIG. 9 is a bottom plan view showing a state in which the outer cap is removed;

FIG. 10 is a front elevational view showing a state in which the outer cap is removed;

FIG. 11 is a rear elevational view showing a state in which the outer cap is removed;

FIG. 12 is a left side elevational view showing a state in which the outer cap is removed;

FIG. 13 is a right side elevational view showing a state in which the outer cap is removed;

FIG. 14 is a top plan view of the outer cap;

FIG. 15 is a bottom plan view of the outer cap;

FIG. 16 is a front elevational view of the outer cap;

FIG. 17 is a left-side elevational view of the outer cap; and,

FIG. 18 is a referential exploded front elevational view.

The broken line showing of a bottle is for illustrative purposes only and forms no part of the claimed design.
